(57) CLAIM

The ornamental design for a cabinet with ironing board, as shown and described.

DESCRIPTION

1. Cabinet with ironing board

1.1 : Perspective

1.2 : Front

1.3 : Back

1.4 : Left

1.5 : Top

1.6 : Bottom

1.7 : Perspective view 2

1.8 : Front view 2

1.9 : Back view 2

1.10 : Left view 2

1.11 : Top view 2

1.12 : Bottom view 2

1.13 : Perspective view 3

1.14 : Front view 3

1.15 : Back view 3

1.16 : Left view 3

1.17 : Top view 3

1.18 : Bottom view 3

1.19 : Perspective view 4

1.20 : Front view 4

1.21 : Back view 4

1.22 : Left view 4

1.23 : Top view 4

1.24 : Bottom view 4

The broken lines depict portions of the cabinet with ironing board that form no part of the claimed design; the dash-dot broken lines define the bounds of the claimed design and form no part thereof; reproduction 1.1 is a front perspective view of the cabinet with ironing board; reproduction 1.7 is a front perspective view thereof in a condition that the top drawer has been open; reproduction 1.13 is a front perspective view of reproductions 1.7 in a condition that the ironing board has been pulled out; reproduction 1.19 is a front perspective view of reproduction 1.13 in a condition that the folding ironing board has been completely unfolded; reproductions 1.2, 1.8, 1.14 and 1.20 are the front views of the reproductions 1.1, 1.7, 1.13 and 1.19, respectively; reproductions 1.3, 1.9, 1.15 and 1.21 are the back views of the reproductions 1.1, 1.7, 1.13 and 1.19, respectively; reproductions 1.4, 1.10, 1.16 and 1.22 are the left views of the reproductions 1.1, 1.7, 1.13 and 1.19, respectively where the right views are mirror images; reproductions 1.5, 1.11, 1.17 and 1.23 are the top views of the reproductions 1.1, 1.7, 1.13 and 1.19, respectively; reproductions 1.6, 1.12, 1.18 and 1.24 are the bottom views of the reproductions 1.1, 1.7, 1.13 and 1.19, respectively.
